ISAAC ICKELHEIMER, OF NEW YORK, N. Y.

Letters Patent No. 89,583, dated May 4, 1869.

IMPROVEMENT IN WATCH-WINDING DEVICE.

The Schedule referred to in these Letters Patent and making part of the same.

To whom it may concern:

Be it known that I, ISAAC ICKELHEIMER, of New York, in the county and State of New York, have invented certain new and useful Improvements in Winding Watches; and I hereby declare the following to be a full, clear, and exact description of the same, reference being had to the accompanying drawings, in which—

Figure 1 is a perspective view of that part of a watch-movement to which my invention relates.

Figure 2 is a longitudinal vertical section of the same.

Figures 3 and 4 are views of detached parts.

The mechanism in all the figures is represented on an enlarged scale, so as to illustrate more clearly the nature of the improvements.

My invention relates to that kind of winding-mechanism described in the patent of F. Robert Theurer, No. 52,505, dated February 6, 1866, and assigned to Charles Kubens & Co., of New York city, that is to say, mechanism whereby the winding may be effected by an oscillating, or back and forth movement of the key, and which will admit of the key being turned in the wrong direction without injury to the parts, thus avoiding that risk which is incurred with ordinary winding-mechanism when the key is turned in the wrong direction, and also avoiding the necessity of removing the key from the winding-pin, or square, or of removing the band from the key, as must be done when ordinary watches are wound up.

The object of my invention is to produce an improved and simplified arrangement of parts.

To effect these results and to this end,

It consists in combining, in the manner hereinafter described, with the ratchet-wheel of the spring-arbor and its retaining-pawl, a plate, carrying the spring-pawl, or click, which moves the ratchet-wheel, and constituting at the same time the winding-stem, or square, to which the key is applied, so that when the plate, by means of its winding-stem, is oscillated in one direction, the click it carries will ride over the ratchet-wheel, and when turned in the other direction the click will engage with and rotate the ratchet-wheel; and my invention consists further in the combination with the winding-plate, when thus combined and arranged with relation to the ratchet-wheel, of a cover or cap, fitting over and applied to said plate, as hereinafter set forth.

To enable those skilled in the art to make and use my invention, I will now proceed to describe the manner in which the same is or may be carried into effect, by reference to the accompanying drawing.

a is the arbor of the spring-barrel, passing up through the bridge *A*, which is mounted in the watch in the usual manner, and carrying the ratchet-wheel *b*, by which it is moved.

Upon the ratchet-wheel is placed the circular plate, or disk *c*, which carries on its under side the click *d*

and its spring *e*, the same being arranged and applied, with relation to the ratchet-wheel, in the manner shown in figs. 3 and 4.

The centre of the plate *c* is raised so as to form a hollow winding-stem, or square *f*, which, when it is in position upon the ratchet-wheel, fits over the upper end of the arbor *a*, the latter forming the axis upon which the plate, or disk revolves.

The retaining spring-pawl, or click *g* is secured to the bridge *A*, or in any other suitable position, so as to engage with the ratchet-wheel, as shown in figs. 1 and 4.

When the parts are thus arranged, it will be seen that if the plate *c* be turned, by means of a key fitting upon the square *f*, in the one direction, the click *d* will engage with the ratchet-wheel, and thus cause the rotation of the arbor *a* and the winding up of the spring, the retaining-click *g* riding over the teeth of the wheel *b*.

When, on the contrary, the key is turned in the opposite direction, the spring-click *d* will ride over the teeth of the ratchet-wheel, which will, however, by means of the click *g*, which engages with it, be retained in position, so that by the back-and-forth movement or oscillation of the key, and consequently of the plate *c*, the winding can be effected easily and expeditiously, and there can be no danger of injuring the parts by reversing the movement of the key.

In order to hold the winding-plate and parts connected with it in place, and at the same time to admit of its free rotation, I place over the same a cover, or cap *h*, formed and secured to the bridge *A*, as represented in figs. 1 and 2.

Its upper part constitutes a socket, which protects the winding-square, while its lower portion is formed so as to fit over and hold in place, upon the spring-arbor *a*, the winding-plate *c*, without interfering with the required movements of the latter.

Having now described my invention, and the manner in which the same is or may be carried into effect,

What I claim, and desire to secure by Letters Patent, is—

1. The combination, with the ratchet-wheel of the main-spring arbor and its retaining-pawl, of the winding-plate, with its square stem and its spring-click, for engaging with the said ratchet-wheel, all constructed and arranged for operation, substantially as herein shown and set forth.

2. The combination, with the parts named in the preceding clause, of the cover or cap, so constructed as to extend over and hold the winding-plate, and to constitute a socket for the protection of the winding-square, as and for the purpose shown and set forth.

In testimony whereof, I have signed my name to this specification, before two subscribing witnesses.

ISAAC ICKELHEIMER.
